CLAIM

The ornamental design for a surgical implant, as shown and described.

DESCRIPTION

FIG. 1 is a top, front, left side perspective view of a first embodiment of a surgical implant according to the present disclosure;

FIG. 2 is a top view of the surgical implant of FIG. 1; FIG. 3 is a bottom view of the surgical implant of FIG. 1; FIG. 4 is a front view of the surgical implant of FIG. 1; FIG. 5 is a back view of the surgical implant of FIG. 1; FIG. 6 is a left side view of the surgical implant of FIG. 1; FIG. 7 is a right side view of the surgical implant of FIG. 1; and,

FIG. 8 is a bottom, front, right perspective view of the surgical implant of FIG. 1 shown in an environment of use. The broken lines in the Figures illustrate portions of the article that form no part of the claimed design.

1 Claim, 3 Drawing Sheets
